UNITED STATES PATENT OFFICE

FREDERICK RIEBEL, JR., AND DEWEY M. DOW, OF TOLEDO, OHIO, ASSIGNEES TO AIR WAY ELECTRIC APPLIANCE CORPORATION, OF TOLEDO, OHIO, A CORPORATION OF DELAWARE

VACUUM CLEANER

Application filed May 20, 1931. Serial No. 538,638.

The present invention relating as nominally indicated to vacuum cleaners, has more particular reference to a novel form of construction and assembly for dust collecting and air filtering bags to be used in combination therewith. The device embodying the principle of our invention is more precisely adapted to be used with a type of suction cleaner which employs a removable sanitary 10 porous paper filtering element.

An object of the present invention is to provide means for conveniently supporting the outer or fabric bag which serves to enclose a removable inner filter bag. A further object is to provide a construction whereby the outer fabric bag may be retained in position upon the vacuum cleaner, while the inner filtering element is removed or installed. It is a further object to provide means whereby 20 the outer bag shall not be susceptible of misplacement upon the cleaner. Another object of the herein described construction is that the bag-supporting elements are readily removable from the bag itself in order to facilitate washing or dry cleaning thereof. Further objects and advantages of our invention shall become manifest as the description proceeds. To the accomplishment of the foregoing and related ends, said invention, then, 30 consists of the means hereinafter fully described and particularly pointed out in the claims.

The annexed drawings and the following description set forth in detail certain mechanism embodying the invention, such disclosed means constituting, however, but one of various mechanical forms in which the principle of the invention may be used.

In said annexed drawings: 40 Fig. 1 is a side elevational view of a general assembly of a vacuum cleaner showing the relative position of the filter bag thereon; Fig. 2 is a plan view of Fig. 1; Fig. 3 is a section taken substantially along the line 3-3 of Fig. 1, showing the lower filter bag rod brackets; Fig. 4 is a section taken substantially along line 4-4 of Fig. 1, and illustrative of the upper bag rod brackets; Fig. 5 is an enlarged perspective view of the combination 45 lower bag rod bracket and cord hock con-

struction; Fig. 6 is a fragmentary enlarged sectional view of the upper assembly of the vacuum cleaner handle; Fig. 7 is an enlarged sectional view of the lower assembly of the vacuum cleaner; Fig. 8 is a fragmentary enlarged side elevation, partly in section of the upper bag rod brackets and switch housing; Fig. 9 is an enlarged section taken substantially upon the line 9-9 of Fig. 6; Fig. 10 is a fragmentary cross sectional view of the spring mounted bag rod brackets; Fig. 11 is an enlarged perspective view of one of the removable bag rod clips; Fig. 12 is an enlarged fragmentary side elevational view showing the lower bag rod brackets; Fig. 13 is a fragmentary enlarged side elevational view of an alternative form of construction for the lower bag rod brackets; Fig. 14 is a section taken substantially upon line 14-14 of Fig. 13; Fig. 15 is an enlarged transverse sectional view taken through the vacuum cleaner handle and filter bag.

Referring more particularly to Fig. 1, the general assembly of the vacuum cleaner is composed of the electric motor 1, a fan casing 2 with the air conducting tubes 3 and 4 attached thereto. A floor contacting tool 5 is mounted upon the end of the air conduit 4. A rotary air valve and transparent dust indicating means 6 is adapted to direct the suction intake through the floor tool 5 or the fibre handle tube 3 at the will of the operator. A fan casing outlet indicated generally at 7 directs the dust and dirt laden air into the interior of the bag 8.

Directing attention to Fig. 7, the outer bag 8, which is composed of cloth or similar material encloses a suitable porous paper filtering element 10. A cone-shaped coupling or adapter 11 is secured to the mouth of the inner paper filter bag 10 by means of the tapered sleeve 12 which is clamped in position on the coupling 11 by means of the threaded ring 13. The fan casing outlet 7 has the flanged conical seat 14 to receive the outer end of the coupling 11. A ball and socket detent 15 is suitably positioned in the outlet 7 in order to removably engage with the complementary groove in the coupling 11. There is also the additional coupling securing means

55

100

consisting of knurled thumb screw 16, which may be employed to maintain a more secure attachment of the coupling 11 to the outlet 7.

As best shown in Fig. 15, the uppermost 5 edge of the outer filter bag 8 is in the form of an openable mouth comprising the marginal sides 20 and 21 with a closing flap 22 positioned therebetween. A pair of hollow metallic rods or tubes 23 and 24 are enclosed with- 10 in the upper edges of the sides 20 and 21 respectively, and extend the entire length of the outer bag 8.

As most clearly illustrated in Figs. 6, 8 and 11, a resilient metallic clip 25 is designed 15 to be positioned upon the outer corners of the sides 20 and 21 of the bag 8. The metallic clip 25 has the resilient prongs 26 which are adapted to removably clamp over the fabric of the bag, as well as the transverse 20 projecting portion 27 with the hole 28 drilled therein. The hole 28 is adapted to register with the tapped ends of the hollow rods 23 and 24. Projecting stud pieces 30 and 31 are then threadably secured to the ends of 25 the bag rods 23 and 24.

By reference to Figs. 8 and 12, which are drawn on the same scale, it will be seen that the diameter of the projecting studs 30 is greater than that of the studs 31. The purpose 30 of the latter type of construction is to insure against misplacement of the filter bag 8 in relation to the vacuum cleaner. The supporting devices for the bag rods which are to be presently described, likewise possess 35 such a differential diameter construction. It will thus be seen that it is possible to secure the bag 8 in proper position only, otherwise the projecting studs 30 and 31 will fail to register with their respective supports.

40 Referring to Figs. 3 and 5, the lower bag rod brackets 34 for reception of the studs 31 have the transversely positioned holes or recesses 32 and 33 and are screwed or otherwise fastened to the top side fan of the casing outlet 7. The bracket 34 also carries the lower electric cord hook 35.

45 Directing attention to Figs. 4, 8, 9 and 10, the upper bag rod latch members 36 and 37 which receive the studs 30, are slidably mounted in the housing 38 which is in turn fastened to the electric switch assembly 9. The switch assembly 9 is composed essentially of the electric toggle switch indicated generally at 39 with the integral annular ring 50 40 which is adapted to slip over the hollow fibre handle tubes 3 and 3'. The switch assembly also includes the insulated knurled ring 41 which is adapted to reciprocably operate the toggle switch 39. The spring cord 55 guard 42 and the upper cord hook 43 are also attached to the switch housing 9. All of the last described component elements constitute a compact and readily installed assembly.

60 The slidably mounted upper bag rod latch 65 members 36 and 37 extend through the

spring housing 38 and have the downwardly and transversely projecting triggers 45 and 46 respectively. Springs 47 and 48 attached to the lugs 49 and 50 serve to tensionally maintain the latch members 36 and 37 in securing attachment with the bag rod studs 30.

65 An alternative form of construction for the lower bag rod brackets is illustrated in Figs. 13 and 14. The hollow fibre tube 3 is secured within the metallic casting 54 which has the projecting ferrule 55 which in turn is adapted to be clamped in the split collar 53. As best shown in Fig. 14, the casting 54 carries the downwardly extending bosses 56 and 57 which have the recesses 58 and 59 respectively. Such recesses 58 and 59 are adapted to serve as a substitute for the lower bag rod brackets 32 and 33.

70 It will thus be seen that we have provided a type of construction for a vacuum cleaner bag support which may be readily removed and installed in position, and correct position only, upon the vacuum cleaner. Furthermore, as illustrated by the dotted lines in Fig. 15, at the mouth of the bag may be opened 75 and the inner filter element replaced or removed while the bag retains its position on the cleaner.

75 Other modes of applying the principle of our invention may be employed instead of the one explained, change being made as regards the mechanism herein disclosed, provided the means stated by any of the following claims or the equivalent of such stated means be employed.

80 We therefore particularly point out and distinctly claim as our invention.

85 1. In combination with a suction cleaner including a handle and a projecting part extending therebelow, a latch member longitudinally slideable relative to said part and projecting therebeyond at each end, one end of said latch member being formed to receive a bag element, and the other end being formed for engagement by an operator.

90 2. In combination with a suction cleaner including a handle and a projecting part extending therebelow near the upper end thereof, a latch member longitudinally slideable relative to said part and projecting therebeyond at each end, one end of said latch member being formed to receive a bag element, and the other end being formed with a trigger.

95 3. In combination with a suction cleaner including a handle and a projecting part extending therebelow, a sheet metal cap secured to said part, including a teat struck upwardly from its bottom wall, a bag latch slidably mounted between the cap and said part, and provided with a down struck teat, and a coil spring hooked at its respective ends upon said teats, disposed between the latch and the cap.

4. In combination with a vacuum cleaner including a handle, and a projecting part extending therebelow, a bag securing latch including a bolt slidably mounted on said part, 5 a perforated member bent upwardly from one end of the bolt, and a trigger bent downwardly from the other end thereof.
5. In a vacuum cleaner, a dust collecting bag, a rigid element secured to the upper margin of the bag, and extending longitudinally of the bag, projections on the ends of said element, and complementary devices having recesses receiving said projections, 10 said projection and recess at one end having diameters greater than the diameters of the projection and recess at the other end of the bag.
6. In combination with a suction cleaner including a handle and a projecting part extending therebelow, a sheet metal cap secured to said part, and provided with notches in its end walls, and a bolt latch bolt slidably between the edges of said notches and said part. 15

Signed by us this 16th day of May, 1931.

25 FREDERICK RIEBEL, Jr.
DEWEY M. DOW.
